UNITED STATES PATENT OFFICE.

WILLIAM H. LOY AND JOHN M. GROFF, OF VICTOR, IOWA.

CREAMING-CAN.

SPECIFICATION forming part of Letters Patent No. 630,247, dated August 1, 1899.

Application filed May 25, 1899. Serial No. 718,154. (No model.)

To all whom it may concern:

Be it known that we, WILLIAM H. LOY and JOHN M. GROFF, citizens of the United States, residing at Victor, in the county of Iowa and State of Iowa, have invented new and useful Improvements in Creaming-Cans, of which the following is a specification.

Our present invention relates to certain improvements in creaming-cans, and has for its object to provide a device of this character which will be extremely simple in construction, cheap of manufacture, and easy and effective in operation.

It is one of the essential features of the invention to provide a creaming-can wherein the interior parts may be quickly and easily removed for the purpose of cleansing such parts.

The invention further comprises means for preventing eddying or whirling of the liquid during the operation of drawing off the contents of the can.

The invention comprises other features of construction and arrangements of parts hereinafter to be described in detail and then more definitely pointed out in the claims which conclude this specification.

In order to enable others skilled in the art to understand, make, and use our said invention, we will describe the same in detail, reference being had for this purpose to the accompanying drawings, wherein—

Figure 1 is a vertical central section of a creaming-can constructed in accordance with our invention. Fig. 2 is a perspective view of the conducting-tube. Fig. 3 is a modified arrangement of conducting-tube.

Referring to the drawings, the reference-numeral 1 designates a can or vessel, which is shown as being tapered in form; but we wish it to be understood that we do not confine ourselves to any particular shape or form of can or vessel. The said can or vessel is provided near its lower end with a conical bottom 2, the sides of which are of comparatively steep pitch and the apex of which is disposed centrally within the can and directed upward toward the top thereof. The upper open end of the can or vessel is closed by a removable top or cover 3 of conical shape, and fixed to the apex of said conical top is a funnel-mouth 4, leaving a strainer 5 remov-

ably seated therein. In practice we prefer to form an annular groove 6 in the funnel-mouth 4, in which the rim of the strainer 5 rests or is seated, and we may, if desired, employ some suitable fastening means for securely holding the strainer within the annular groove 6, although this is not thought to be essential. The said cover is further provided on its under side, at the apex thereof, with a depending tube 7, which extends a slight distance down within the can or vessel.

The reference-numeral 8 indicates a conductor-tube, the upper end of which when in position for operation telescopes over the lower end of the depending tube 7 on the cover 3. The lower end of the said conductor-tube is flared outward in the form of a cone 9, and the extreme lower edge of said cone is crimped or corrugated, as at 10, around its entire circumference to provide a plurality of gaps or outlet-openings for the passage of the fluid from the conductor-tube into the can or vessel, and this crimped or corrugated edge we consider to be an important feature of the invention, since it acts during operation to forcibly distribute the water through the milk, so as to cause a rapid separation and ascent of the cream.

In order to prevent eddying or whirling of the fluid within the can or vessel during the operation of drawing off the water and thin milk, which eddying or whirling would tend to mix the cream with the other fluid, we have provided the conductor-tube 8 with two or more lateral wings or blades 11, which extend from a point near the top of the tube to a point adjacent to the corrugations or crimps in the cone 9. When the conductor-tube is in position for operation, it will be seen that the extreme lower corrugated edge of the cone 9 rests or seats in the annular groove formed between the conical bottom 2 and sides of the can, as clearly shown in Fig. 1 of the drawings.

The can or vessel is provided at the lowest point adjacent to the bottom with a draw-off cock or faucet 12, and above said faucet is a sight tube or gage 13, which will indicate the level of the liquid within the can or vessel. The can is further provided with suitable handles 14, as usual.

In Fig. 3 of the drawings we have shown a

modified form of conductor-tube, in which instance the lower conical end 15 thereof is made adjustable or distensible in order that it may be fitted to vessels of different size.

- 5 The said conical end 15 is split along the line 16 and the edges made to overlap in order to accommodate for adjustments, the parts being held secure when adjusted to the proper size by means of a set-screw 17. By this construction it will be seen that the conical end of the conductor-tube, may be applied to vessels of different size, and since the upper end of said tube has a telescoping connection with the depending tube on the top or cover it will be understood that the conductor-tube will also be suited to cans or vessels of different heights. This construction and adjustment of the parts, whereby they are suited to cans or vessels of different sizes, is 20 considered to be an important and desirable feature of the invention.

The operation of the invention may be briefly stated as follows: The milk having been first placed within the can either by pouring 25 through the conductor-tube or otherwise, water of a comparatively low degree of temperature is then introduced through the conductor-tube, (it being understood that the parts are in the position indicated in Fig. 1,) and passing down the latter it strikes the conical bottom and enters between the latter and the conical end of the conductor-tube in the form of a thin sheet or film, and continuing in its course it is forced by pressure upward 30 through the gaps formed by the corrugations or crimps in the said conical end of the conductor-tube, by which the said thin sheet or film is divided into narrow streams, which flush the inner surface of the can and are also distributed through the entire body 35 of milk, thus causing a rapid separation and formation of the cream, which latter, owing to its specific gravity being less than that of the water, quickly rises to the top. The liquid is allowed to remain at rest for a few moments, and then the water and thin or blue milk are drawn off through the cock or faucet, after which the cream may be removed in a similar manner.

40 50 It will be seen that all the interior parts of the device are removable and separable, and they can thus be cleansed with facility, thus insuring the sweetness of the milk and cream.

A practical test of the device has demonstrated that cream can be separated from milk in from three to five minutes.

What we claim, and desire to secure by Letters Patent, is—

1. In a creaming-can, the combination with 60 the can-body having a cone-shaped bottom, of a removable distributor-tube having a similar cone-shaped lower end adapted to fit over the said cone-shaped bottom of the can, and a removable cover for the can having a funnel-mouth which telescopes within the said conductor-tube.

2. In a creaming-can, the combination with the can-body having a cone-shaped bottom, of a conductor-tube having a similar cone-shaped lower end adapted to fit over the said cone-shaped bottom of the can, the lower edge of said conductor-tube being crimped or corrugated to provide a plurality of gap-openings around the edge thereof adjacent to the inner side walls of the can, and a cover for the can having an opening therein which communicates with the conductor-tube. 75

3. In a creaming-can, the combination with the can-body having a cone-shaped bottom, of a conductor-tube having a similar cone-shaped lower end adapted to fit over the said cone-shaped bottom, a plurality of radial wings carried by the conductor-tube, and a cover for the can having an opening therein which communicates with the conductor-tube. 80

4. In a creaming-can, the combination with the can-body having a cone-shaped bottom, of a conductor-tube having a similar cone-shaped lower end adapted to fit over the said conical bottom of the can, a line of crimps or corrugations around the lower coned edge of the conductor-tube, radial wings carried by the conductor-tube, and a cover for the can having an opening therein which communicates with the upper end of the conductor-tube. 90

5. In a creaming-can, the combination with a can-body, of a conductor-tube removably mounted therein and having a flared or conical end the lower edge of which is crimped or corrugated to provide a row of circumferential gap-openings, and a removable cover for the can, having an opening therein which communicates with the said conductor-tube. 100

6. In a creaming-can, the combination with a can-body, of a conductor-tube removably mounted therein and having a flared lower end, the bottom edge of which is crimped or corrugated to provide a series of gap-openings, a removable cover for the can, and an open tube carried by said cover and depending within the can and having a telescoping connection with the upper end of the conductor-tube. 110

7. In a creaming-can, the combination with a can-body, of a conductor-tube removably mounted therein and having a flared lower end, the bottom edge of which is crimped or corrugated to provide a series of openings at such edge, radially-extending blades carried by said conductor-tube, a removable cover for the can, and an open tube carried by the cover and depending within the can and having a telescoping connection with said conductor-tube. 120

8. In a creaming-can, the combination with a can-body, of a conductor-tube removably mounted therein and having a flared and corrugated lower end, a removable cone-shaped cover for the can, a funnel-shaped mouth carried by said cover, a strainer located in said

mouth, and a tube depending from the cover and opening into the said funnel-mouth and having a telescoping connection at its lower end with the conductor-tube.

5 9. In a creaming-can, the combination with a can-body, having a cone-shaped bottom, of a conductor-tube removably mounted in said can and having a flared or conical lower end adapted to fit over the cone-shaped bottom of

10 the can, the lower edge of said conducting-tube being crimped or corrugated to provide a gap-opening at such end, radial wings carried by said conductor-tube, a removable cover for the can having an opening therein,

15 a funnel-mouth surrounding said opening, a strainer located in said mouth, a tube depending from the funnel-mouth into the can and

telescoping into the conductor-tube, and a draw-off cock or faucet for the can.

10. In a creaming-can, the combination with the can-body, of a conducting-tube removably mounted therein and having a distensible cone-shaped lower end, and a removable cover for the can having an opening therein communicating with the upper end of the conducting-tube.

In testimony whereof we have hereunto set our hands in presence of two subscribing witnesses.
